UNITED STATES PATENT OFFICE.

ALFRED G. F. KUROWSKI, OF BROOKLYN, NEW YORK, ASSIGNOR TO UNDERWOOD TYPEWRITER COMPANY, OF NEW YORK, N. Y., A CORPORATION OF DELAWARE.

TYPEWRITING MACHINE.

Application filed January 28, 1921. Serial No. 440,665.

To all whom it may concern:

Be it known that I, ALFRED G. F. KUROWSKI, a citizen of the United States, residing in Brooklyn Borough, in the county of 5 Kings, city and State of New York, have invented certain new and useful Improvements in Typewriting Machines, of which the following is a specification.

This invention relates to typewriting machines, and particularly to the key-action thereof, an object being to provide means for readily changing the degree of pressure necessary to be exerted upon the keys to drive the type to print.

15 A feature of the invention resides in the provision of means whereby the leverage of the system of levers included in the type-action may be varied, to thereby vary the pressure on the keys, and, preferably, this change 20 of leverage is effected in connection with the key-lever itself, the particular embodiment 25 of the invention taking the form of arms slidably mounted on the key-levers, and carried by a bracket which may be adjusted, so 30 that the pivotal point of the arms, which is also the pivotal point of the key-levers, may be adjusted to or from the point of pivotal connection between the type-bars and the key-levers. In this way, the pressure necessary 35 to drive the type may be made harder or softer, according to the desire of the operative.

Other features and advantages will hereinafter appear.

35 In the accompanying drawings,

Figure 1 is a side elevation of an Underwood typewriting machine, showing my improvement applied thereto.

Figure 2 is a horizontal sectional view.

40 Figure 3 is a perspective view of connections from two key-levers, showing the means for shifting the fulcrum thereof.

Figure 4 is an elevational view, showing the position of some of the parts, with a key 45 in normal position, and showing, in dotted lines, the changed position of some of the parts when the key is depressed to the dotted-line position.

Figure 5 is a perspective detail of a portion of the bracket for supporting and guiding the arms which form the pivotal connections for the key-levers.

Figure 6 is a perspective view of a portion of a key-lever, showing an arm slidably attached thereto.

Figure 7 is a view similar to Figure 4, but showing the parts in a different position of adjustment.

Referring to Figure 1, the frame of the typewriter is shown at 1, and this frame is modified by having its rear portion slightly deeper than usual, in order to accommodate some of the mechanism used in connection with my improvements. As usual, the type-bars 2 are adapted to swing about a fixed pivot 3, said type-bars having the usual driver 4, connected thereto, at 5, said driver being pivoted at 6 in a fixed support 7. The driver 4 is in the form of a bell-crank, the right-hand portion, as seen in Figure 1, being forked, as shown, to embrace a pin 8, carried by a key-lever 9, said key-lever having the usual key 10, connected thereto, by which said key-lever may be rocked and the type-bar driven to cause either of the type 11, carried thereon, to strike against the platen 12. The platen 12 is supported, as usual, in a carriage 13, which slides upon a rear rod 14, and is also supported, near its central portion, on a movable rod 15, said carriage having a roller 16, which engages said rod 15. This rod, as is usual in machines of the Underwood construction, is adapted to be rocked to shift from lower to upper case, and said rocking is effected by a rocking member 17, pivoted at 18. The carriage is fed, in letter-spacing, by the usual escapement which includes a dog-rocker, indicated as a whole by the numeral 19, said dog-rocker acting to move fixed and movable escapement-dogs into and out of engagement with the usual escapement-wheel 20, having connected thereto an escapement-pinion 21, with which engages a rack 22, carried by the typewriter-carriage, the carriage itself being drawn towards the

left by the usual carriage-spring (not shown). All of the parts above described are usual in machines of the Underwood type.

5 It is desirable to vary, at times, the amount of pressure required on the key-levers to drive the type to printing position, and, in the particular embodiment of the invention shown, this is accomplished by varying the 10 leverage of the lever-system between the key and the type. Preferably, each of the key-levers is lengthened, and, instead of the lever having a fixed pivot, I provide arms 23, each of which has a bent-up portion 24, 15 having a hole 27^a therethrough, said arm also having a lug 25, which is bent over to loosely engage the edges of a key-lever, as shown particularly in Figure 6. The arms 23 for all of the key-levers are pivotally 20 mounted in a bracket 26, and are held in place by a fulcrum-rod 27 extending through the holes 27^a. Each arm is supplied with an independent tension-spring 28, having a screw 29, by which it may be 25 adjusted in a manner well known in the art, this screw 29 being threaded into a hole in the bottom of the bracket 26. For convenience in manufacture, the bracket 26 consists of a casting having a base portion 30 30 and upstanding side portions 31. The portion supporting the fulcrum-rod 27 is made in a separate piece 32 and is slotted, as shown in Figures 3 and 5, to properly guide the arms. In order to properly guide the 35 ends of the key-levers, a guiding rod 33 passes through a slot in the ends thereof, said slot being of such length as to permit full movement of the lever at all times. The arms 23 form the points about which the 40 key-levers pivot, and the bracket 26, which carries these arms, is movable transversely of the machine by means of screws 34, one on either side of the machine, said screws passing through threaded holes 35, formed 45 in the sides of the bracket 26, said screws being supported at their ends in brackets carried by the frame of the typewriter. Each screw has at its left-hand end, as shown in Figure 3, a spiral gear 36, each of which 50 is in mesh with another spiral gear 37, carried by a shaft 38, one end of which projects through the casing and has a knob 39, secured thereto, by which the shaft may be rotated and the bracket 26 adjusted.

55 If the bracket 26 is positioned, as indicated in Figure 4, the force necessary to depress a key 10 will be less than that required to depress said key if the parts were adjusted as indicated in Figure 7, because, in 60 Figure 7, the distance between the pivotal point 27 of the key-lever and the pivotal point 6 of the type-driver is greater than the distance between the same points in Figure 4, while the distance between the 65 point 6 and the key 10 remains the same. It

will be noted, however, that, by reason of the fact that the spring 28 is carried by the bracket, to be moved along the key-lever 9 concomitantly with the movement of the pivot 27, it always exerts its pressure to return the key-lever to normal position at a constant distance from its pivotal point. By reason of the fact that the bracket 26 requires some space in the rear portion of the typewriter-frame, this frame portion 70 has been made a little deeper, as already suggested, and the connections from the space-bar and the case-shift have been modified somewhat, in order to avoid any interference of parts. Thus, the space-bar 40 has 75 an upstanding arm 41 connected thereto, said bar pivoting at 42, and to its arm 41 is connected a link 43, which has a portion 44 for engagement with the escapement-rocker. Also, the shift-key 45 is bent up, so as to 80 avoid interference with other parts, as is likewise the case-shift detaining lever 46, said lever being pivoted at 47 and being moved to release the case-shift by the usual latch 48, operated on by a pin 49, carried 85 by the shift-key-lever.

Variations may be resorted to within the scope of the invention, and portions of the improvements may be used without others.

Having thus described my invention, I 95 claim:

1. In a typewriting machine, the combination with a key-lever, of an arm slidably mounted on said lever, a bracket pivotally supporting said arm, and means for adjusting said bracket.
2. In a typewriting machine, the combination with key-levers, of an arm slidably mounted on each key-lever, a bracket pivotally supporting all of said arms, said bracket having threaded holes at either end thereof, and screws engaging said holes, to thereby adjust said bracket.
3. In a typewriting machine, the combination with key-levers, of an arm slidably mounted on each key-lever, a bracket pivotally supporting all of said arms, said bracket having threaded holes at either end thereof, screws engaging said holes, and means for turning both screws simultaneously, to thereby adjust said bracket.
4. In a typewriting machine, in combination, a pivoted key-lever, a spring for returning said lever, said spring engaging the same at a constant distance from its pivot, a type-bar, pivotal connections from said type-bar to said key-lever, and means for concomitantly moving both said spring and the pivot of said key-lever nearer to, or farther from, the point of connection between the same and the type-bar connections.
5. In a typewriting machine, the combination with a key-lever formed of a single piece, of a pivotally-mounted arm slidable on said key-lever, the pivot of said arm act-

ing as a bearing about which said key-lever pivots, and means for shifting the position of the pivot of said arm.

6. In a typewriting machine, the combination with a key-lever formed of a single piece, of a pivotally-mounted arm slidable on said key-lever, the pivot of said arm acting as a bearing about which said key-lever

pivots, means for shifting the position of the pivot of said arm, and guiding means for the end of said key-lever.

ALFRED G. F. KUROWSKI.
